UNITED STATES PATENT OFFICE.

LESLIE T. SUMMERS, OF DALLAS, TEXAS.

COMBINATION MERCHANDISE DISPLAY AND COOLING CASE.

Application filed March 24, 1927. Serial No. 178,018.

This invention relates to store furniture and fixtures and it has particular reference to a combination merchandise display and cooling case, designed especially for displaying and dispensing merchandise such as vegetables, fruits, butter and eggs, and many other commodities likely to become spoiled unless kept in a cool, moist place, and the principal object of the invention resides in the provision of a case as set forth wherein is provided an ice chamber with provisions for containing bottled beverages.

Another object of the invention is to provide a merchandising case of the character described having a series of compartments, all of which are cooled by moist air emitted from a common source, which source, as stated, likewise provides a means for cooling beverages, consequently defraying the cost of maintenance of the fixture.

Still another important object of the invention resides in the provision of interchangeable display chambers, in which is contained an example of the merchandise contained within the case.

Broadly, the invention comprehends an improvement in store fixtures especially adapted for that character of store wherein the patrons thereof are required to make their own selections and purchases, and a case constructed according to the present invention greatly aids the purchaser to select his merchandise with care and with readiness.

With these foremost objects in view, the invention has particular reference to certain salient features of construction and arrangement of parts by which the foregoing objects are attained, and which will be set forth hereinafter as the description proceeds, taken in connection with the accompanying drawings, wherein:

Figure 1 represents a perspective view of a store fixture constructed according to the present invention.

Figure 2 is a view in elevation showing the display compartments.

Figure 3 is a sectional view of the fixture on lines 3—3 of Figure 2, and

Figure 4 is a detail view of one of the display compartments in Figure 2.

Continuing now more in detail with the drawings, 1 designates a case, which, as apparent particularly in Figure 1 has a central ice chamber 2 provided with a hinged trans-

parent cover 3. On either side of this cover 3 is provided hinged covers 4, permitting ac-

cess to the compartment 5, shown in the sectional view, Figure 3. A floor partition 6 divides this compartment from the lower compartment 7, to which access is obtained through doors 8. The upper compartment 5 is also provided with smaller doors 9, to enable one in front of the cabinet to remove merchandise therefrom.

Immediately beneath the ice chamber 2 on the floor 6 may be kept for sale, perishable vegetables, such, for example as lettuce, radishes, and similar merchandise, and due to the apertures 10 in the floor of the ice receptacle drippings from the ice is directed onto the vegetables to aid in preserving them. The vegetables are then drained of water by permitting the latter to pass through apertures 11, onto the floor 12, thence through apertures 13 onto the sloping basin 14 to pass out through drain 15.

Notice will be taken of the display compartments 16 in Figure 3 especially, and the detail view thereof in Figure 4. Each of these compartments or receptacles is provided with a hinged transparent lid 17, having a latch 18 in order that the merchandise may be carefully placed and the lid closed thereon preparatory to insertion into its respective place in the case proper, as illustrated in Figure 2. This section 19, behind which the display receptacles repose is likewise composed of glass. It will also be observed that the rear wall of each receptacle 16 is perforated as shown at 20, in order that air will in circulating through the perforations 21 in the interior perpendicular wall 22, pass through each of the display compartments, to maintain fresh condition of the display therein.

In the ice compartment 2, as illustrated in Figure 3, may be kept bottled goods 23, and in so doing, the merchant is enabled to defray the actual operating expense of the fixture, which is very small, since no great amount of ice is required to properly cool its contents, due to the added advantages of the air circulation obtained through the multiplicity of perforations described, aided by the air spaces, intermediate the compartments 2 and 7, and 16 and 7.

Manifestly, the construction shown is capable of some variation and such variation as is in keeping with the appended claims is considered within the spirit of the invention.

What is claimed is:

1. A fixture of the character described comprising a case having a central ice chamber

- and provided with perforations in its floor; said compartments and ice chamber; said means consisting of compartments having transparent lids slidable endwise into said case so as to be vertically disposed therein; and means to permit a circulation of air through said first compartments and said display compartments. 35
- 5 receive and dispose of drippings from said ice chamber after having penetrated said compartments; a multiplicity of display compartments slidable endwise into said case rearwardly of said first compartments and ice chamber to be vertically disposed, and means to permit circulation of air through said display compartments from said first compartment. 40
- 10 2. A fixture of the character described comprising a case having superimposed compartments; means to gain access to said compartments, an ice chamber disposed centrally of said case above said compartments; the floors of said compartments and ice chamber having perforations therein; a catch basin disposed below the lowest compartment to receive and dispose of drippings from said ice chamber after penetrating said compartments; display means situated rearwardly of
- 15 20

3. A store fixture of the character described comprising a case having superposed compartments, the upper of which is adapted to contain ice, each of said compartments having apertures in the floors thereof; a basin disposed below the lowest of said compartments to receive drippings from said ice compartment, and to permit of air circulation; a series of removable display compartments 45 rearwardly of said first compartments, and disposed on a relative vertical plane to provide an air space intermediate the latter and said first compartments, and means to permit circulation of air through said display compartments.

In testimony whereof I affix my signature.
LESLIE T. SUMMERS.
